WALTER R. DIEHL, OF PITTSBURGH, PENNSYLVANIA.

ANTICREEPING DEVICE.

1,241,202.

Specification of Letters Patent. Patented Sept. 25, 1917.

Application filed December 19, 1916. Serial No. 137,767.

To all whom it may concern:

Be it known that I, WALTER R. DIEHL, a citizen of the United States, and a resident of Pittsburgh, Allegheny county, Pennsylvania, have invented a new and useful Improvement in Anticreeping Devices, of which the following is a specification.

This invention relates to an anti-creeping device for railway rails.

10 The object of the invention is to provide an anti-creeping device which is simple in its construction and cheap and easy to manufacture, and which acts instantaneously and positively to prevent the creeping of a 15 railway rail in either direction longitudinally of the rail. A further object of the invention is to provide in a device of the character described a rocker member or dog for preventing creeping of the rail, and a 20 tie-plate so arranged as to hold the rocker member in operative position with respect to the rail without the use of springs or other means for maintaining the contact between the rail and rocker member. A still 25 further object of the invention is to so proportion and arrange the rocker member and its supporting means that the rocker member is completely inclosed by the supporting means and the rail and thus protected 30 from displacement or rusting.

In the accompanying drawings, Figure 1 is a cross section through a railway rail and longitudinal section through a steel tie, showing the anti-creeping device in position. Fig. 2 is a plan view of a steel tie embodying the anti-creeping device of the present invention; Fig. 3 is a cross section through a tie on the line 3—3 Fig. 2, showing the anti-creeping device in operative engagement with the under surface of the rail; Fig. 4 is a plan view of a tie-plate for use with wooden ties and embodying the device of the present invention; Fig. 5 is an enlarged cross sectional view of the rocker member of the anti-creeping device; and Fig. 6 is a diagrammatic side elevation of the same.

The rocker member or dog 1 is, as shown, of the general form of an equilateral triangle and is arranged to be supported in a suitable recess in inverted position in such manner that it may normally rock in either direction upon its apex as an axis of rotation. The rocker member 1 is arranged to extend transversely of the rail, and preferably a substantial part of the width thereof.

As shown in Figs. 1 to 3 inclusive, a steel tie 2 is provided with an indented or recessed portion 3 extending transversely of the rail and in which the rocker member 1 rests. The rocker member is preferably blunted along its lower extremity as by means of a longitudinal bead 4 so that it may rest in the recessed portion 3 without cutting of this portion under pressure from above, and along its upper surface is provided with a longitudinal concavity arranged to form horns 5, 5^a at the opposite edges of the upper surface. When the railway rail 6 is placed in position with the 70 rocker member lying in the recess in the tie, the horns 5, 5^a, which are preferably made sharp, though preferably not brought to a knife edge, will tend to bite slightly into the skin of the under surface of the 75 rail, thus securing a positive engagement between the rail and anti-creeping device, the rocker member 1 being preferably formed of a steel which is hard enough to provide this slight cutting action, while also 80 possessing sufficient toughness to withstand the crushing stress incurred while the rail is being forced into position. The form and rigidity of the supporting means for the 85 rocker member hold it firmly in position during laying of the rail, so that this biting action is readily effected. It will be apparent that when once the rail is in position on the tie, the rocker member will not be called upon to support any of the weight 90 of the rail, since the cutting action of the horns 5, 5^a will readily bring the rocker member into adjusted position with the horns extending into the shallow grooves on the under portion of the rail which they 95 have themselves cut. The sides 7 of the recessed portion 3 are preferably arranged substantially at right angles to each other with the lower and narrower portion of the rocker member resting thereon at their point 100 of intersection.

The operation of the device is best illustrated by referring to Fig. 5 of the drawings. With the parts in operative position, if the rail 6 tends to creep in the direction of the arrow "A", the rocker member will tend to rotate in such manner as to lower the horn 5^a and to raise the horn 5. Since no room for such rotation is provided, the tendency of the horn 5 to rise serves to secure the rail against this creeping movement. If there is a tendency for the rail to

creep in the direction of the arrow "B" Fig. 5, the tendency to rotation of the rocker member, which is to so rotate as to raise the horn 5^a, will likewise serve to prevent creeping of the rail in that direction. It will be seen that the arrangement and proportioning of the recess 3, and the rocker member 1 is such that it is impossible for the rocker member to be so displaced as to bring either 10 or both of its edges 5, 5^a out of contact with the under surface of the rail; and because of the construction of the upper surface of the rocker member, providing these horns or edges, the action of the device is positive 15 and practically instantaneous, since the horns 5, 5^a, tend to rotate through an arc of relatively great radius, thus increasing the sensitiveness of the device. The angle of rotation is also such, due to the design and 20 relative arrangement of parts, that the horns 5, 5^a, cannot exert any planing action on the under surface of the rail, but that the tendency will be merely to bite more deeply into the rail along the arc C—C as 25 shown in Fig. 5 of the drawings.

The device remains operative for so long a period of time as the tie remains in condition for service, since the wear on the rocker member 1 is compensated for by the 30 wear between the upper surface of the tie and the under surface of the rail, and a mutual settling of the tie and rail will not affect the relative position of the rocker member. It will also be observed that the 35 rocker member 1 is completely inclosed between the recess 3 of the tie and the under surface of the rail 6 so that it is protected from rust or from wear due to dust or grit.

As illustrated in Fig. 4, the invention 40 may be employed with the ordinary form of tie-plate used with wooden railway cross ties. In such case the tie-plate 8 is cast to provide a recess 3 similar to that in the steel tie 2 and the rocker member 1 is placed 45 in this recess which extends transversely of the rail. The action of the device in such case is similar in all respects to that obtained with the use of a steel cross tie.

The advantages which the present invention 50 provides over prior devices of a somewhat similar nature lie in the employment of a recess in the body of a steel cross tie or tie-plate, without the use of special devices or extensions for supporting the rocker member, and in the construction of the 55 rocker member itself. This construction of the rocker member as shown, causes an instantaneous and positive response to any tendency toward creeping of the rail, since an increased radius of rotation is provided by the use of a narrow rocking base and widely spaced points of contact with the under surface of the rail. The formation of the sharp edges of the horns also renders the 60 action more positive since the rocker mem-

ber is caused to bite slightly into the rail during the placing of the latter. The formation of the recess and the construction of the rocker member also, as hereinbefore stated, cause the horns to rotate through an arc of 70 such radius that they are prevented from exerting any planing action such as might tend to injure the under surface of the rail.

What I claim is:—

1. An anti-creeping device for railway 75 rails comprising a rocker member extending transversely of the rail and having a concave upper surface, and means for supporting said member and normally maintaining it in contact with the under surface of the 80 rail.

2. An anti-creeping device for railway rails comprising a rocker member extending transversely of the rail and provided at the edges of its upper surface with parallel 85 horns extending throughout the length of said member, and means for supporting said member and maintaining the horns thereof normally in contact with the under surface 90 of the rail.

3. An anti-creeping device for railway rails comprising a rocker member arranged to extend transversely of the rail and provided on its upper surface with sharp rail-engaging means, and rigid means for maintaining said rail-engaging means in contact with the under surface of the rail, said rocker member and supporting means being so arranged that tendency of the rail to creep in either longitudinal direction will 100 be met and checked by the consequent tendency to rotation of the rocker member.

4. An anti-creeping device for railway rails comprising a rocker member and supporting means therefor, said rocker member 105 being supported on a relatively narrow base and having a relatively broad upper surface having edges arranged to engage the under surface of the rail, and said supporting means being so arranged as to permit rotation of the rocker member in either direction longitudinally of the rail and to prevent displacement of the upper edges thereof from contact with the under surface of 110 the rail.

5. An anti-creeping device for railway rails comprising a rocker member and means for inclosing and supporting the same, said rocker member being supported on a relatively narrow base and having a relatively broad upper surface having edges arranged to engage the under surface of the rail, and said supporting means being so arranged as to permit rotation of the rocker member in either direction longitudinally of the rail 115 and to prevent displacement of the upper edges thereof from contact with the under surface of the rail.

6. An anti-creeping device for railway rails comprising a rocker member, and a 120

rigid rail supporting member provided with a transverse recess in the body thereof arranged to inclose and support said rocker member in contact with the under surface of the rail, said rocker member and recessed supporting member being so arranged as to resist movement of the rail in either direction longitudinally thereof.

7. An anti-creeping device for railway rails comprising a rocker member, and a rigid rail supporting member provided with

a transverse seat arranged to inclose and to support said rocker member in contact with the under surface of the rail, said rocker member and supporting member being so arranged as to resist movement of the rail in either direction longitudinally thereof. 15

In witness whereof, I have hereunto set my hand.

WALTER R. DIEHL.
